INFANT'S GARMENT

Samuel Berman, Hartford, Conn.

Application June 6, 1952, Serial No. 292,150

2 Claims. (Cl. 2—111)

1

This invention relates to an infant's garment and, more specifically, to a shirt for diaper-age children which is particularly adapted to support an abdominal belt or truss.

It is common practice to apply and support a pressure pad on the umbilical region of newly born infants to prevent or guard against rupture of the navel. In a great many cases, a rupture is unavoidable and in such cases a pressure or rupture pad must be worn for sufficient time to permit healing. In either event, the pad and/or the abdominal belt which carries the pad are sources of a great deal of discomfort to the child, not only because of the pressure, but also because of skin chafing frequently results from poorly supported belts.

It is the general aim of the present invention to provide an infant's shirt which will not only provide the usual protection expected of such garments, but which will in addition provide adjustable means for positioning and supporting an abdominal belt and the accompanying umbilical pad and which will protect the infant's skin from the said belt and pad.

Other more specific objects and advantages of the invention, as well as features of construction, will become apparent to those skilled in the art from the following description of the attached drawing.

In the drawing,

Fig. 1 is a front view of an infant's shirt which incorporates the present invention;

Fig. 2 is a rear view of the shirt;

Fig. 3 is a view similar to Fig. 1 with an abdominal belt and pad in place over the shirt and showing how the shirt is arranged to support the belt;

Fig. 4 is similar to Fig. 3 but shows the shirt completely arranged to support the belt;

Fig. 5 is a front view of a shirt incorporating a second embodiment of the invention; and

Fig. 6 is a front view of a shirt incorporating a third embodiment.

In each of Figs. 1-4, there is included an exemplary illustration of a commercially available type of infant's shirt 10 having added thereto the structure of the present invention. For an understanding of this invention, it will suffice to point out that the particular shirt shown in Fig. 1 includes sleeves 12, 12 and an overlapping body 14, i. e., the body of the shirt 10 overlaps at the front of the infant and the overlapping portions are secured to each other in conventional fashion as, for example, by tie strings 16.

The aforescribed shirt as well as the shirts

2

illustrated in Figs. 5 and 6 are most commonly produced in knit cotton fabrics or a mixture of cotton with wool, rayon or other yarn. Because of the inherent nature of the knit fabric, the shirts are easily stretched out of shape if they are used in some fashion to support other articles like diapers, for example.

In accordance with my invention I reinforce the shirt so that the same can be used as the support means for a conventional abdominal belt or truss. Stretching of the shirt fabric is prevented because the reinforcing means provide the principal support for the said belt.

The above mentioned reinforcing means comprise a pair of elongated fabric tapes 18, 18, each of which is stitched as at 20, 20 adjacent its longitudinal edges to the shirt body 14 so as to extend from the bottom of the shirt at the front, up and over one of the shoulders, to the bottom 20 of the shirt at the back. Preferably, the tapes 18, 18 are interconnected across the back of the shirt by a third tape 22 similarly stitched, the last mentioned tape providing additional support to prevent stretching of the shirt 10.

As will be apparent from Figs. 3 and 4, the tapes 18, 18 are utilized to support an abdominal belt 24 so that a rupture pad or pressure pad 26, carried by the belt, will be located in the umbilical region upon the infant. The belt 24 is conventional and is provided with a buckle 28 so that it can be adjusted about the body of the infant for proper pressure upon the umbilicus. It is the customary practice to secure such a belt to the body of the infant beneath the infant's shirt. Obviously, the belt is a source of discomfort to the child as particularly manifested by skin rash. Furthermore, the belt frequently slips from the proper position and thus doesn't serve its purpose. If the belt is tightened sufficiently to prevent slipping, it is too tight about the child's abdomen.

In accordance with the present invention, the aforementioned disadvantages are avoided. The belt is placed on the outside of the shirt whereby the shirt protects the child's skin from chafing and the shirt is adapted to support the belt in a manner which prevents slippage thereof. As previously mentioned, the reinforcing means on the shirt provides the principal support means for the belt.

More specifically, the reinforcing tapes 18, 18 are each provided with adjustable fastening means adjacent their opposite ends so that the said tapes and the bottom of the shirt can be 55 folded over the belt 24 to prevent shifting thereof.

In the embodiment shown in Figs. 1 to 4, the fastening means comprise a male snap button 30 secured at each end of each tape 18 and a plurality of cooperating female button members 32, 32 spaced from the corresponding male member 30 and spaced from each other. The snap fastening members 30 and 32 are conventional articles of commerce and are carried by the tapes 18, 18 so that no portion of said members can engage the infant's skin and cause irritation.

It will be readily understood that each male fastening member 30 can be brought into selective engagement with any one of the adjacent female members 32. The selection afforded by the plurality (three shown) of female members 15 permits adjustment of the loop taken in the bottom of the shirt and the vertical position of the belt is adjusted accordingly. When the bottom portion of the shirt has been looped over the belt in the desired position, the overlapping portions of the shirt body 14 may be fastened together over the belt by tie strings 34, 34 so that the shirt body will be neatly folded in the proper position.

It will be quite apparent that the shirt will not be stretched nor will it in any way bind the child due to the emplaced abdominal belt. Substantially all of the weight of the belt is carried by the reinforcing tapes 18, 18 suspended from the shoulders of the child and the shirt merely serves to protect the child's skin from chafing etc.

While the aforescribed embodiment of the invention has been described in connection with one type of commercially available infant's shirt, it should be understood that the structure of the present invention can be applied to other types of shirts. In Figs. 5 and 6 a sleeveless, non-overlapping shirt 40 has been shown as another exemplary shirt to which the invention may be applied. In Fig. 5 a modified embodiment of the supporting means has been shown wherein a pair of tie strings 42, 42 secured in spaced relation adjacent each end of each tape 18 are employed in the place of the previously described snap fasteners. The strings 42, 42 can be tied in adjusted positions to adjust accordingly the extent of the belt enfolding loop taken in the bottom of the shirt and thereby select the vertical position for the abdominal belt.

Since each of the shirts to which the aforescribed embodiments of the invention are applied is to be folded over the abdominal belt, it is preferable that the shirt bodies be slightly longer than ordinary. However, it is within the scope of the present invention to modify slightly the support structure so that it can be conveniently applied to a shirt of conventional length.

Fig. 6 illustrates the last mentioned embodiment of the invention and as shown, the rein-

forcing tapes 18, 18 are adapted to fold upwardly from the bottom of the shirt to embrace the abdominal belt without also folding the bottom of the shirt. The modification is accomplished 5 easily, by not extending the stitching 20, 20 to the ends of the tapes 18, 18 and by stitching across the said tapes as at 44, 44. Thus, the ends of the tapes can be folded over a belt to secure the same in the desired vertical position by means 10 of the snap fastening members 30 and 32 shown, or by means of tie strings such as shown in Fig. 5.

From the foregoing description it will be understood that in accordance with the present invention, conventional infant's shirts can be modified to properly support an abdominal belt upon a child by applying thereto the structure described. The shirt can be worn in the usual way to accomplish its normal function and in addition, by providing support for the abdominal belt, it greatly increases the comfort of the infant who must wear the belt.

It should also be understood that the invention is not limited to the described embodiments except as indicated by the claims which follow.

25. I claim:

1. An infant's garment adapted for abdominal support comprising in combination, a shirt body having shoulder portions; a plurality of reinforcing tapes secured to the outside of the shirt body and extending substantially longitudinally thereof over the said shoulder portions, an abdominal belt surrounding said body; and fastening means on said tapes located above and below said belt adapted to be interconnected and secure said tapes in adjusted folded positions over said belt.
2. An infant's garment adapted for abdominal support comprising in combination; a shirt body having shoulder portions; a plurality of reinforcing tapes each secured to the said body and extending substantially longitudinally of the body from the bottom portion of the front, over the said shoulder portions, to the bottom portion of the rear thereof, an abdominal belt surrounding said shirt body, and means on each of said tapes located above and below said belt at the front and at the rear of the shirt body adapted to secure said tapes in adjusted folded positions over said belt.

50. SAMUEL BERMAN.
